UNITED STATES PATENT OFFICE.

JOHN W. BOWERS, OF MARIETTA, OHIO.

ADJUSTABLE SCAFFOLD.

1,200,303.

Specification of Letters Patent.

Patented Oct. 3, 1916.

Application filed March 14, 1916. Serial No. 84,067.

To all whom it may concern:

Be it known that I, JOHN W. BOWERS, a citizen of the United States, resident of Marietta, in the county of Washington and State of Ohio, have made a certain new and useful Invention in Adjustable Scaffolds; and I declare the following to be a full, clear, and exact description of the same, such as will enable others skilled in the art to which it appears to make and use the invention, reference being had to the accompanying drawings, and to letters or figures of reference marked thereon, which form a part of this specification.

The invention has relation to scaffolds, having for its object to provide an improved adjustable scaffold, combining ease and convenience of assemblage with the greatest possible rigidity in adjusted position.

Other objects and advantages will hereinafter appear.

The invention consists in the novel construction and combinations of parts, as hereinafter set forth.

In the accompanying drawings, illustrating the invention, Figure 1 is a rear view of the invention, with parts broken away, the standards being located upon uneven ground. Fig. 2 is a section on the line 2—2, Fig. 1, the upper staging bracket being shown as thrown back in dotted lines. Fig. 3 is a plan view of the invention. Fig. 4 is a detail plan view of the lower staging bracket, showing the post in section. Fig. 5 is a detail sectional view of the post, the channeled bracket, and the cross brace connection. Fig. 6 is a detail sectional view of the interfitting brackets and the cross brace connection.

In the drawings the numeral 2 designates posts or standards, spaced apart and connected by a cross-brace 3 and diagonal braces 4. Each post is provided at the inner side thereof with a pipe or rod 5, the upper ends of the diagonal braces having slidable engagement with said pipe at 6, and the ends of the cross braces 3 having slidable engagement with said pipe at 7, through the medium of channeled brackets 8, closely engaging the pipe and bent partially around the posts, to engage both the inner and outer sides thereof, removable bolts 9 loosely engaging alined perforations of the leaves of the brackets and any one of a series of perforations 11 of each post, to hold the cross-

brace in position as adjusted longitudinally of the posts. The pipes or rods 5 being offset from the faces of the posts 2, and the brackets 8 closely engaging both posts and rods, the brace connection 3 will effectually prevent any twisting movement of said posts. The lower ends of the diagonal braces are slidably engaged with the cross-brace through two-part interfitting brackets 12, 12', each two-part bracket embracing extensible sections 3' of the cross-brace, a bolt 13 engaging slots 13' of said sections, alined perforations of the bracket parts and a perforation of the lower end of the diagonal brace relating thereto. Upon loosening the screw-cap 14 of said bolt, the two-part brackets may be slid longitudinally of the cross-brace, and the sections of the cross-brace may be extended or slid together, to provide for various adjustments.

A rearwardly extending inclined prop 15, composed of two downwardly-converging members 15', is also slidably engaged at the upper end of each member with the rod 5, intermediately of the diagonal brace and the cross-brace connections with said rod, the members of the prop being also composed each of extensible sections, having a clamp connection 17. The lower ends of the prop members are provided respectively with loops 18, designed to be engaged by a securing peg 18'.

Mounted upon the top of each post is an angular staging bracket 19, hinged at its rear end at 20 to and resting upon the top of a support member 21, composed of a strut 22, a horizontal top 23 resting upon the post and a vertical back 24 fitting against the post, bolts 25 connecting the support member to the post. This staging bracket may be swung backwardly upon its hinge, as shown in dotted lines, Fig. 2, when its back arm will rest squarely against the back of the support member, with its horizontal arm 26 extending rearwardly, in position to bear against a wall of a building, to brace the post at the top, in which case the prop hereinafter described would not be used. The horizontal arm 26 of this staging bracket is provided with an extensible part 27, having a clamp-screw 28, the upper staging 30 resting upon this extensible part. A lower staging bracket 31 is supported by a block and tackle 31' from the support member of the upper bracket, and is provided with inturned flanges 33, engaging

slidably vertical grooves 34 of the post. This lower bracket is also provided with an extensible outer part 35, having a clamp-screw 36 and upon which rests the lower 5 staging 37.

Each pipe 5 engages at its upper end with the vertical arm of an L-form iron 38, said iron being horizontally pivoted to the post at 39, and the lower end of said pipe is 10 engaged by an elongated pin 40, sliding within a sleeve 41, carried by a U-form iron 42 upon the post. A clamp-screw 43 of the sleeve has engagement with said pin to hold it in engagement with the pipe. Upon 15 loosening this clamp-screw the pin will fall from engagement with the pipe, which may now be turned to one side upon its upper pivotal connection as a center, and the prop members and the diagonal brace members 20 may be slid downwardly and removed from the pipe, which may then be swung back to normal position and the elongated pin re-engaged therewith. This pin is prevented from dropping from the sleeve by a stop 44 upon the post, so that the pin and the sleeve 25 are always at hand, ready for use.

The lower staging bracket, as it is adjusted longitudinally of the posts by the block and tackle, is secured in position as 30 adjusted by bolts 46, engaging the perforations 11 of the post, said perforations serving a double purpose, being also designed for engagement by the bolts 9 of the channeled brackets.

35 For support of the scaffold upon uneven ground, each post is provided with an extension leg 47, engaging brackets 48 of the post, having a clamp-screw 49 to secure the adjustment.

40 The extensible member of each staging bracket is provided with a forward projecting spike 50, the spikes being adapted for engagement with the wall of a building, and co-operating with the prop to support the 45 scaffold.

When the rod or pipe 5 is swung to one side upon its upper pivotal connection with the post, as stated, the channeled brackets 8 will be moved therewith from engagement 50 with the posts, the securing bolts or pins 9 being first removed.

I claim:

1. In an adjustable scaffold, a post, a staging bracket thereupon, a longitudinal rod having at one end pivotal connection and at the other end rigid detachable connection with said post, and a brace member having slidable engagement with said rod. 55

2. In an adjustable scaffold, posts, staging brackets thereupon, offset longitudinal rods upon said posts, and a transverse brace having slidable laterally rigid engagement with said posts and said rods. 60

3. In an adjustable scaffold, posts, staging brackets thereupon, offset longitudinal rods upon said posts, a transverse brace having slidable adjustment upon said posts and slid- 65 able engagement with said rods, and diagonal braces having slidable adjustment upon said rods and upon said transverse brace. 70

4. In an adjustable scaffold, posts, staging brackets thereupon, offset longitudinal rods having at one end pivotal connection and at the other end rigid detachable connection with said posts, and a transverse brace having slidable laterally rigid engagement with said posts and said rods. 75

5. In an adjustable scaffold, posts, staging brackets thereupon, offset longitudinal rods having at one end pivotal connection with 80 said posts, bearing devices upon said posts, adjustable securing means carried by said bearing devices and capable of engagement with the free ends of said rods, and a transverse brace having slidable laterally rigid engagement with said posts and said rods. 85

6. In an adjustable scaffold, posts, staging brackets thereupon, offset longitudinal hollow rods having at one end pivotal connection with said posts, bearing devices upon 90 said posts, longitudinally adjustable securing pins carried by said bearing devices and capable of engagement within the free ends of said hollow rods, and a transverse brace having slidable laterally rigid engagement 95 with said posts and said rods.

7. In an adjustable scaffold, posts, staging brackets thereupon, offset longitudinal rods upon said posts, brace brackets having slid- 100 able laterally rigid engagement with said posts and said rods, and a transverse brace rigidly secured upon said brace brackets.

8. In an adjustable scaffold, posts, staging brackets thereupon, offset longitudinal rods upon said posts, brace brackets having a 105 close sliding engagement with three faces of said posts and adjustably fixed thereupon and having slidable engagement with said rods, and a transverse brace rigidly secured upon said brace brackets. 110

In testimony whereof I affix my signature, in presence of two witnesses.

JOHN W. BOWERS.
